UNITED STATES PATENT OFFICE.

ERAPHIA A. SWIHART, OF RANDALL, KANSAS.

HEATING ATTACHMENT FOR INCUBATORS, BROODERS, AND THE LIKE.

1,283,962.

Specification of Letters Patent. Patented Nov. 5, 1918.

Application filed June 6, 1916. Serial No. 101,938.

To all whom it may concern:

Be it known that I, ERAPHIA A. SWIHART, a citizen of the United States, residing at Randall, in the county of Jewell and State 5 of Kansas, have invented certain new and useful Improvements in Heating Attachments for Incubators, Brooders, and the like; and I do hereby declare the following to be a full, clear, and exact description of the invention, such as will enable others skilled in 10 the art to which it appertains to make and use the same.

This invention relates to new and useful improvements in heating attachment for incubators, brooders and the like and the principal object of the invention is to provide an automatically controlled means for regulating the heat within the device.

Another object of the invention is to provide a device which will admit fresh air to 20 the brooder or incubator should the device become overheated.

A further object of the invention is to provide a simply controlled thermostatic 25 means including a pair of relatively adjustable dampers which are arranged so that should any of the rods become bent the dampers may be readily adjusted to their proper relative positions.

With these and other objects in view, the invention consists in the novel combination and arrangement of parts which will be 30 fully set forth in the following specification and accompanying drawing, in which:—

Figure 1 is an end view of a brooder constructed in accordance with this invention, and

Fig. 2 is a longitudinal sectional view through the device.

Referring to the drawing the numeral 1 designates the brooder box or body having secured to one end wall a bracket 2, the end walls of the brooder are formed with openings 3 arranged in alinement to receive the 40 heating drum or tube 4 one end of which is provided with the apertured closure 5, while the opposite end communicates with the interior of the flue 6. This flue 6 is adapted to receive the hot gases from a lamp chimney of a suitable lamp positioned beneath the lower open end of the flue and the upper end of said flue is left open to be closed by a suitable damper which will be more fully hereinafter described. A suitable bracket 7 45 is attached to the end wall of the box 1 to which the bracket 2 is connected and these

brackets are arranged to pivotally support the damper controlling arms which will be more fully hereinafter described.

A thermostat 8 is mounted on a suitable 60 bracket 9 within the box 1 and this bracket 9 carries the standard 10 on which is pivotally mounted the lever 11 one end of which bears on the upper side of the thermostat 8 while the opposite end has pivotally connected thereto as at 12 a rod 13, the upper end of which is externally screw threaded as at 14 to coöperate with the threads of the wing nuts 15 and 16.

A lever 17 is pivotally connected at 18 to 70 the bracket 2 and the rear end of this lever is apertured to receive the rod 13 while the opposite end of the lever carries the damper 19 which is positioned directly over the upper open end of the flue 6. The thumb nut 75 16 bears on the upper side of the lever 17 and it will thus be seen that upon turning the thumb nut 16 the position of the damper 19 may be varied without moving the rod 13.

Pivoted in the bracket 7 is a lever 20 80 which like the lever 17 is formed with an opening to receive the upper threaded end of the rod 13 and the thumb nut 15 is adapted to bear on this lever in order that the same may be adjusted without moving the rod. 85 The rear end of the rod 20 is threaded as at 21 and an internally threaded weight 22 is threaded on the portion 21 to act as a counterbalance for the damper designated by the numeral 23 which is positioned over the 90 opening 24 in the top wall of the brooder. This opening 24 is to allow the warm air from the brooder to escape should the interior of the brooder become overheated and in order to supply fresh air to the brooder 95 suitable openings 25 are formed in the side walls as will be clearly seen upon reference to Fig. 2.

It will be apparent from the foregoing that in use a lamp is set below the lower open end 100 of the flue 6 and it will be apparent that the hot gases will pass upwardly through the flue and when the wafer 19 closes the same it will be apparent that the gases will be directed through the drum 4 and out 105 through the opening in the end wall 5. As the temperature rises within the brooder it will be apparent that the thermostat 8 will become operative and after passing a predetermined point it will be seen that the 110 lever 11 will be moved to pull the rod 13 downwardly thereby lifting the damper 19

from its position on the upper end of the flue 6 and simultaneously lifting the damper 23 from its position over the opening 24 thereby allowing the gases passing through 5 the flue 6 to pass outwardly to the atmosphere without passing into the drum 4 and also allowing the warm air within the brooder to escape. As soon as the air has returned to its normal degree of heat within 10 the brooder, it will be apparent that the thermostat 8 will operate to allow the rod 13 to rise and thereby move the covers or dampers 19 and 20 to each of their operative positions. It will also be apparent that 15 should the relative positions of the dampers 19 become accidentally changed the same may be readily adjusted by the adjusting of the thumb nuts 15 and 16.

While in the foregoing there has been 20 shown and described the preferred embodiment of this invention, it is to be understood that such changes may be made in the combination and arrangement of parts as will fall within the spirit and scope of the 25 appended claim.

Copies of this patent may be obtained for five cents each, by addressing the "Commissioner of Patents, Washington, D. C."

What is claimed is:—

In a brooder, a brooder box having an opening formed in its top, a heater for heating the interior of the box and having an escape opening, a damper normally closing 30 said escape opening, a rod pivotally supported by said box, a damper carried by said rod, for closing the opening in said top, a counter balancing weight adjustably carried by said rod, a thermostat, a pivoted lever 35 adapted to be operated by said thermostat, a vertical rod connected to said lever, a lever connected to said first-named damper, said last-named lever and said pivoted rod adjustably connected to said vertical rod for 40 simultaneous operation upon movement of said vertical rod by operation of said thermostat.

In testimony whereof I affix my signature in presence of two witnesses.

ERAPHIA A. SWIHART.
